MICHAEL ASSEN AND FREDERICK P. EIKMANN, JR., OF ST. LOUIS,
MISSOURI.

GUIDE-CASING FOR BOILER-TUBE CLEANERS.

No. 841,917.

Specification of Letters Patent.

Patented Jan. 22, 1907.

Application filed March 19, 1906. Serial No. 306,820.

To all whom it may concern:

Be it known that we, MICHAEL ASSEN and FREDERICK P. EIKMANN, Jr., citizens of the United States, residing at St. Louis, State of Missouri, have invented certain new and useful Improvements in Guide-Casings for Boiler-Tube Cleaners, of which the following is a full, clear, and exact description, reference being had to the accompanying drawings, forming a part hereof.

Our invention has relation to improvements in guide-casings for boiler-tube cleaners; and it consists in the novel construction and arrangement of parts more fully set forth in the specification and pointed out in the claims.

In the drawings, Figure 1 is a middle vertical section through a water-tube boiler, taken on the line 1 1 of Fig. 2, showing our invention applied thereto. Fig. 2 is a front elevation of Fig. 1. Fig. 3 is a side elevation of the casing detached with part of the wall broken away, and Fig. 4 is a sectional detail showing the water-supply hose coupled to the hydraulic or turbine-driven tube-cleaner confined within the casing.

The object of our invention is to provide a casing which will effectively and positively guide into position a boiler-tube cleaner, whereby the necessity of handling the cleaner or bringing it into contact with the hands of the operator is entirely dispensed with, the walls of the casing serving to protect the hands against injury should unauthorized persons set the cleaner into motion.

A further object is to facilitate the insertion of the cleaner into its proper tube of the boiler and finally to facilitate the cleaning of water-tubes (or fire-tubes) generally, all as will hereinafter more fully appear from a detailed description of the invention, which is as follows:

Referring to the drawings, B represents a section of a water-tube boiler, the same being provided with water-tubes 1, terminating in the supporting-plate 2, between which and the head 3 of the boiler is a water space or chamber 4. The ends of the tubes 1 project a fraction of an inch beyond the outer face of the inner plate 2, access to the tubes being had through hand-holes 5, formed in the head 3 opposite thereto. To clean a tube, it is

a common practice to pass a cleaner through a hand-hole 5 opposite the tube, one hand being inserted through an adjacent hole 5 into the water-space 4 to properly guide it into the tube to be cleaned. Should the cleaner be accidentally set into motion while being thus held in the hand in the space 4 before it is inserted into its proper tube, the hand thus guiding it would be in danger of injury or mutilation, and it is to avoid such accidents that our casing was devised.

A very common form of cleaner is one such as shown in the drawings, consisting of a cylinder 6, one end of which is connected, by means of a coupling 7, to a water-supply hose 8, leading to any source of water-supply, (operating under a head or positive pressure,) the current passing through the hose setting into operation a turbine-motor within the cylinder 6, to the shaft 9 of which motor are pivotally attached a series of cutters 10, which remove the incrustation C, formed within the tube, by their centrifugal action. This form of turbine-cleaner is well known on the market and requires no detailed description, as it forms no part of our invention, but is here alluded to to better illustrate the application of our invention. This consists of a tubular casing 11, terminating at its inner end in a flange 12, which is adapted to close over the projecting end of a tube 1, the casing being inserted through the hand-hole 5 and being of sufficient length to project a suitable distance outside the head 3 when fully inserted. That portion of the peripheral surface of the casing confined within the water-chamber 4 is provided with discharge-openings or slots 13, through which the wash-water escapes into the boiler when the tubes are being cleaned. The forward portion of the casing 11 is provided with a pair of lugs 14, between which is pivotally mounted a latch 15, whose inner terminal head 16 is forced by a spring 17 to engage the wall of an adjacent hand-hole 5 when the casing is inserted into any hand-hole, as previously described. By this means the casing becomes locked in position once being inserted into a hand-hole. The outer end of the casing is provided with a contracted hollow screw-tip or nipple 18, through which the hose 8 may pass freely, the space between the hose

and walls of the said nipple, however, being sufficiently closed or contracted against any material passage of the wash-waters which must flow out through the openings 13.

5 The operation of the device is best described by a reference to Figs. 1 and 4. The casing 11 is first passed over the end of the hose 8 until the hose projects a suitable distance beyond the rear end of the casing, 10 after which the coupling 7 is attached thereto and screwed to the cylinder 6 of the motor, whereupon the cylinder, with its cutter-heads 10, is drawn wholly into the casing, Fig. 4. Thus the casing serves as a housing for the cylinder 6 and its cutter-heads, and by attaching the casing opposite any particular tube 1 the cleaner is in position to enter it without further handling on the part of the operator. All that is then required is for the 15 attendant or helper to turn the water on into the hose, when the pressure or hydrodynamic head will not only set the cutters into rotation, but the cylinder will advance through the tube until the whole length 20 thereof is cleaned. When that is done, the operator stops the motor, pulls back the hose, and draws the cleaner back into the casing, when the latter may be removed and inserted opposite another tube, the latch 15 25 always locking with the walls of an adjacent hand-hole. Thus the entire series of boiler-tubes may be cleaned without the necessity of the hands of the operator ever coming in contact with the dangerous cutters of the 30 cleaner. When the boiler is cleaned, the cylinder 6 may be uncoupled from the hose and put away, and the casing may be hung up with the hose, or by unscrewing the casing 11 from the nipple 18 the casing may be 35 put away and the nipple alone hung up with the hose. The nipple, while acting as a seal against the discharge of the waste waters through the outer end of the casing, at the same time serves to prevent the accidental 40 withdrawal of the cleaner through said front end, so that the cleaner remains permanently incased and may be handled with impunity until the end of the cleaning operation. The casing 11 when once in position opposite 45 any tube 1 forms practically an extension of the tube, the cleaner being free to advance from the extension into and through the tube, as shown in the illustration in Fig. 1.

Having described our invention, what we claim is—

55

1. In combination with a boiler-head having a series of hand-holes opposite the water-tubes thereof, a casing inserted through a given hole and against the end of the tube, a cutter with a stem or shaft freely passing through said casing, the wall of the casing being provided with peripheral openings discharging into the space between the boiler-head and the plate in which the water-tubes terminate, substantially as set forth. 60

65

2. In combination with a boiler-head having a series of hand-holes opposite the water-tubes thereof, a casing inserted through a given hole and against the end of the tube, a cutter with a stem or shaft freely passing through said casing, the wall of the casing being provided with peripheral openings discharging into the space between the boiler-head and the plate in which the water-tubes terminate, and a latch on the casing engaging the wall of an adjacent hole, substantially as set forth. 70

75

3. In combination with a boiler-head having a series of hand-holes opposite the water-tubes thereof, a casing inserted through a given hole and against the end of the tube, a cutter with a stem or shaft freely passing through the casing and a spring-controlled latch on the casing engaging the wall of an adjacent hole, substantially as set forth. 80

85

4. A tubular casing having an outer contracted hollow nipple for the passage of a hose, and having a rear perforated portion for the discharge of waste waters, the rear end of the casing terminating in a flange for engaging the end of a boiler-tube, a cutter with a stem or shaft freely passing through the casing and a spring-controlled latch mounted at the forward portion of the casing for engaging the wall of a hand-hole formed in the boiler-head opposite a tube contiguous to that with which the casing is in temporary engagement, substantially as set forth. 90

95

In testimony whereof we affix our signatures in presence of two witnesses.

MICHAEL ASSEN.

FREDERICK P. EIKMANN, JR.
